OTHER PUBLICATIONS

Pending design U.S. Appl. No. 29/725,280, filed Feb. 24, 2020, inventor Abel et al. Per rule 609.07.

Primary Examiner — Mark A Goodwin*(74) Attorney, Agent, or Firm* — Polson Intellectual Property Law, PC; Margaret Polson**(57) CLAIM**

We claim the ornamental design for a movable barrier operator, as shown and described.

DESCRIPTION

FIG. 1 is a first perspective view of a movable barrier operator in accordance with our new design;

FIG. 2 is a second perspective view thereof;

FIG. 3 is a bottom plan view thereof;

FIG. 4 is a top plan view thereof;

FIG. 5 is a first end elevation view thereof;

FIG. 6 is a second end elevation view thereof;

FIG. 7 is a first side elevation view thereof; and,

FIG. 8 is a second side elevation thereof.

Broken lines in the drawings form no part of the claimed design.
